UNITED STATES PATENT OFFICE.

FREDERICK CRANE, OF NEWARK, NEW JERSEY.

DESIGN FOR A HARNESS-TERRET.

SPECIFICATION forming part of Design No. 12,285, dated May 31, 1881.

Application filed April 11, 1881. Term of patent 7 years.

To all whom it may concern:

Be it known that I, FREDERICK CRANE, of Newark, in the county of Essex and State of New Jersey, have originated and invented a new and useful Design for a Terret for Harness; and I do hereby declare that the following is a full, clear, and exact description thereof, reference being had to the accompanying drawings, forming a part of this specification, in which—

Figure 1 shows a perspective view of a terret for harness made after my design, and Fig. 2 a front view of the same.

The object of this design is to produce a terret of tasteful form, and one that can be easily polished and burnished by the ordinary machines and tools used for this purpose. The inner portions and the curved outer portion are free from sharp angles, and the whole from undercut parts.

The following are the essential new features which make up the design: First, the band extending over the top from $a a'$ to a'' , and curved as shown; second, the lower portion of the loop, as shown at $b b' b''$, joined, as shown, to the lower portion of the band at or near the ends $a a''$, the band and this lower portion completing the loop; third, the base C, surmounted by the swell b' , and joined to the lower portions, $b b''$. These are the separate new features, and when joined together in the manner shown produce a new, tasteful, and

easily-manufactured article, and possessed of such characteristics as not to be mistaken for any design for a similar article heretofore made. 35

This design may be ornamented by inlaying, gilding, coloring, and the like, as ordinarily practiced, without departing from the nature of this invention, which is intended to cover the separate features hereinbefore enumerated individually and in combination.

Having thus described my invention in designs for terrets, what I claim, and desire to secure by Letters Patent, is—

1. The overextending band, as shown, from 45 a to a'' , curved as shown.
2. The base of the loop, composed of the parts $b b' b''$, in combination with the lower portions of the band, $a a''$, substantially as shown. 50
3. The base C, in combination with the lower portion of the loop, as represented at $b b' b''$, substantially as shown.
4. The combination of the band $a a' a''$, the lower portion of the loop $b b' b''$, and the base 55 C, all substantially as set forth.

In testimony that I claim the foregoing as my own I affix my signature in presence of two witnesses.

FREDERICK CRANE.
